[57] CLAIM

The ornamental design for an electrical connector, as shown and described.

DESCRIPTION

FIG. 1 is a top view of an electrical connector according to a first embodiment showing our new design;

FIG. 2 is a front view of the connector according to the first embodiment;

FIG. 3 is a bottom view of the connector according to the first embodiment;

FIG. 4 is a rear view of the connector according to the first embodiment;

FIG. 5 is an enlarged, right side view of the connector according to the first embodiment, the opposite side being a mirror image;

FIG. 6 is an enlarged sectional view taken along 6—6 in FIG. 2 of the connector according to the first embodiment, with exposed signal contacts shown in elevation;

FIG. 7 is an enlarged sectional view taken along 7—7 in FIG. 2 of the connector according to the first embodiment;

FIG. 8 is a top view of the connector according to a second embodiment;

FIG. 9 is a front view of the connector according to the second embodiment;

FIG. 10 is a bottom view of the connector according to the second embodiment;

FIG. 11 is a rear view of the connector according to the second embodiment;

FIG. 12 is an enlarged right side view of the connector according to the second embodiment, the opposite side being a mirror image; and,

FIG. 13 is an enlarged sectional view along 13—13 in FIG. 9 of the connector according to the second embodiment, with exposed contacts shown in elevation.
